UNITED STATES PATENT OFFICE.

ALBERT G. BIERBACH, OF MILWAUKEE, WISCONSIN, ASSIGNOR OF ONE-HALF TO HECTOR RIGGS, OF SAME PLACE.

TRAMWAY.

SPECIFICATION forming part of Letters Patent No. 339,257, dated April 6, 1886.

Application filed August 13, 1885. Serial No. 174,290. (No model.)

To all whom it may concern:

Be it known that I, ALBERT G. BIERBACH, of Milwaukee, in the county of Milwaukee and State of Wisconsin, have invented new and useful Improvements in Tramways; and I do hereby declare the following to be a full, clear, and exact description of said invention, reference being had to the accompanying drawings, and to the letters or figures of reference marked thereon, which form a part of this specification.

My invention relates to improvements in tramways for street-cars; and it pertains to that class from which the cars are suspended and operated above the street.

The construction of my invention is explained by reference to the accompanying drawings, in which—

Figure 1 represents two tramways of my improved form, suspended, respectively, one upon each side of the supporting-columns, from one of which tramways a car is shown suspended. Fig. 2 represents a side view of the same device shown in Fig. 1. Fig. 3 is a detail showing an end view of the journals of the rollers of the car-supporting truck provided with anti-friction roller-bearings. Fig. 4 is a longitudinal section of the roller and journal-bearings shown in Fig. 3. Fig. 5 represents a cross-section of the tramway and one of the supporting-brackets used between the columns and one of the supporting-rollers. Fig. 6 is a side view of Fig. 5. Fig. 7 is an enlarged view of one of the side arms which extend outward upon the respective sides of the columns, in which arm a cross-section of the tramway is shown. Fig. 8 is a side view of Fig. 7.

Like parts are represented by the same reference-letters throughout the several views.

My tramway and the truck operating thereon, consisting of a slotted tube, A, rollers B, hangers E E, and a connecting-bar, D, are substantially the same as shown in the patents for fire-escapes, Nos. 278,310 and 287,410, now owned by myself. The hangers E E are loosely fitted at their upper ends to the axles of the rollers B, from which they are suspended, and they are connected at their lower ends with the respective ends of the car. The two hangers, thus arranged, are connected with each other by the horizontal connecting-bar D. At

quite long distances apart, varying from about a quarter to a half an ordinary city block, I erect substantial columns E, which are firmly anchored to the ground, and from their upper ends two outward-extending arms, F F, are provided, of such length as will allow the required space for a car to pass upon each side of the columns without contact therewith. From these arms F F are suspended my slotted tubular tramways A; but owing to the great space between the columns and arms it becomes necessary to provide for additional supports for the tramway between the columns; and to accomplish this end I provide strong metallic frame-work G G, formed, preferably, of metallic bars and plates, secured together by bolts or rivets, which frame-work lies edge-wise upon the respective other ends of the arms F F, and upon their lower edges are affixed a series of brackets or hangers, H. The brackets H are thus attached at short intervals by bolts, their lower ends being so shaped as to nearly surround the tube, leaving space only between their lower ends for the passage of the hangers of the truck. To give greater stability to the frames G G, they are braced or tied together by a rod, I. From the hangers C C rods or bars of iron extend either down through the center of the car or around it, as shown, and they are affixed at their lower ends to the supporting bed-pieces J J. The car thus suspended may be drawn either by a cable to which motion is communicated by a stationary engine or by any desired motive power. I have, however, shown one form of device for communicating motion from a motive power within the car, which device consists in affixing to the tubular support or way a toothed bar, K, (shown in Fig. 8,) in which a toothed wheel, L, is adapted to operate. The wheel L is affixed to the car, and is connected with and rotated by any desired motor, and as the teeth of the rotating wheel traverse the toothed bar within the stationary supporting-way the car is caused to move forward. I do not, however, desire to limit myself to the peculiar form of motor used, as other forms of driving machinery may be employed.

Having thus described my invention, what I claim as new, and desire to secure by Letters Patent, is—

1. The combination, with a series of sup-

porting-columns, of a series of supporting side arms extending outwardly from said columns, a metallic frame-work resting upon the outer ends of said arms and extending from one arm 5 to another, a slotted tubular tramway, a series of hangers or brackets securing said tramway to said metal frame-work, a truck consisting of rollers and hangers connected together, and a car suspended from said truck, operating in 10 said tramway, substantially as and for the purpose specified.

2. The combination, with the slotted tubular tramway A, suspended from a series of suitable columns along a highway, of a toothed

bar, K, and with a car suspended by rollers 15 and hangers from said tubular tramway, of a toothed wheel, L, operating in said toothed bar and adapted to be operated by a motive power within said car, whereby the car is propelled along said way, substantially as set 20 forth.

In testimony whereof I affix my signature in presence of two witnesses.

ALBERT G. BIERBACH.
